(57) **CLAIM**

The ornamental design for a backpack, as shown and described.

DESCRIPTION

FIG. 1 is a front perspective view of a backpack, showing my new design with a front flap in a lowered position; FIG. 2 is a front perspective view thereof, with the front flap in a raised position;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2;

FIG. 8 is a bottom plan view of FIG. 2;

FIG. 9 is a rear perspective view of FIG. 2;

FIG. 10 is a front perspective view showing a top zippered pouch in an open position;

FIG. 11 is a front perspective view showing a dice tray removed from the backpack; and,

FIG. 12 is a front perspective view showing a bottom zippered pouch in an open position.

The broken lines in FIGS. 1, 4, and 11 showing a logo depict portions of the backpack that form no part of the claimed design. The remaining broken lines depict stitching, and do form part of the claimed design.
